IMPROVEMENT IN BOILER-FLUE BRUSHES.

ROBERT KING, OF BROOKLYN, NEW YORK, ASSIGNOR TO T. PROSSER & SON, OF NEW YORK CITY.

Letters Patent No. 60,013, dated November 27, 1866.

SPECIFICATION.

TO ALL WHOM IT MAY CONCERN:

Be it known that I, ROBERT KING, of Brooklyn, in the county of Kings, and State of New York, have invented a certain new and useful Improvement on Helical Wire Brushes; of which the following is a full, clear, and exact description, reference being had to the accompanying drawing, forming part of this specification, and in which—

Figure 1 represents a longitudinal view of a helical wire brush, constructed according to my improvement; and,

Figure 2, a transverse section thereof, taken as indicated by the line xx , in fig. 1.

Like letters refer to like parts in both figures.

Helical wire brushes, or flue-brushes, as they are sometimes called from their use in cleaning out tubular boiler flues, have usually been constructed of steel wires of spring temper, made flat at their ends, to act as scrapers or cutters, and arranged in the form of a helix round a twisted wire stock composed of two or more strands, and serving to receive between them and hold midway of their length the steel wires of the helix. An eye at one end of the stock and screw-shank at the opposite end serve, by means of a rope and rod or rods, to work and pass the brush through the tube or flue. Such brushes, however, have been defective in the arrangement of the wires of the helix, which should have free open spaces between each other at their working ends that require to be flexible, while the interior portion of the helix around the stock should be close packed by the wires, so as to form a firmer hold of the latter. This cannot be effected, however, or but imperfectly so, by the present mode of construction; that is, by holding the several wires to or in the stock midway of their length, and so that each two adjacent ones project to an equal extent from opposite sides of the stock, as to leave sufficient width of spaces between the wires at their working ends does not admit of sufficiently close packing of them around the core or stock to give them a steady hold the one upon the other, and distributes the flexibility too generally throughout their length, while to arrange them in closer connection round the core brings their working ends too near each other to operate with the desired effect. This difficulty, however, my invention obviates; and it consists in arranging the brush-wires so that they protrude further from or on one side of the stock than on the opposite side, whereby a close packing of the wires is obtained at the centre around the core, and an open or free space left between them at their working ends. For the information of others whom it may concern, I will proceed to describe my invention, with reference to the accompanying drawing, in which—

A is the core, or stock, formed of twisted wire, or strands, in the usual manner, and provided with an eye, *a*, at one end, and screw-shank, *b*, at the other, to operate the brush as helical brushes are usually worked. The core, A, has arranged round it in the form of a helix the spring-tempered steel wires, *c c*, *d d*, *e e*, *f f*, similarly, so far as their general disposition and hold of them by the stock, through the strands of which they pass, to other helical wire brushes, but differing therefrom in the following important respect: The wires, which may be of equal length, instead of being held midway of their length, so as to project equally from opposite sides of the stock, are arranged to protrude more from one side than the other, so that two adjacent wires form, the one a short and the other a long projection from or on the same side of the stock, and reverse projections respectively on the opposite side thereof, thereby making alternate wires to project equally, longer on one and shorter on the other side of the core. In this way is a steady hold given to the wires by their close lapping or packing in the central space lying between the core and working ends of the wires, while said wires at their working or outer ends have the necessary increased space left between them and desirable flexibility, by reason of the wires alternately only protruding from the same side of the stock to form working ends, the intermediate wires not so protruding though similarly projecting on the opposite side of the core.

What I claim herein as new and useful, and desire to secure by Letters Patent, is—

A helical wire brush, in which the wires are arranged to protrude unequally from opposite sides of the core or stock, substantially as shown and described.

ROBERT KING.
